UNITED STATES PATENT OFFICE.

HENRY ARTEMAS THOMPSON, OF FARMINGTON, MAINE.

WRENCH.

SPECIFICATION forming part of Letters Patent No. 286,653, dated October 16, 1883.

Application filed February 9, 1883. Renewed September 17, 1883. (No model.)

To all whom it may concern:

Be it known that I, HENRY A. THOMPSON, of Farmington, in the county of Franklin and State of Maine, have invented a new and useful Improvement in Wrenches; and I do hereby declare that the following is a full, clear, and exact description of the same.

My invention relates to wrenches, and is more particularly an improvement upon that form of wrench shown in Letters Patent of the United States granted me on the 2d day of November, 1880. In that patent is shown a form of wrench in which the jaws are formed with angular recesses, whereby they are adapted to grasp the corners of a nut, and are specially fitted to act as wrenches for removing and applying the nuts from the ends of carriage-axles.

My invention consists of a detachable hammer-head adapted to be held in the aforesaid jaws, thus converting the wrench temporarily, while the hammer-head is so held, into a hammer.

In the accompanying drawings, Figure 1 represents a side elevation of the wrench. Fig. 2 represents a central longitudinal section of the same. Fig. 3 represents a section of Fig. 1, with the hammer head or piece in place, as represented in said figure. Fig. 4 represents the hammer head or piece detached.

In these figures, *a* indicates the shank; *b*, the fixed, and *c* the movable, jaw. These jaws are double, one side of each being formed with an angular recess, 1, and the opposite side with the ordinary form of jaw, the first serving as the jaws of a wagon-wrench, and the latter as jaws of an ordinary monkey-wrench. The shank *a* is made polygonal, and a sleeve, 2, of the movable jaw is fitted to slide thereon. An arm, 3, on this sleeve extends back to the rounded part 4 of the shank, carrying on the end a ring, 5. The round part is threaded, and a nut (preferably with handle, as shown) serves to force the jaws together and clamp any object held between them. The handle *B* is made of wood, and is screwed upon the threaded end of the shank.

It has been common heretofore to form a hammer upon some part of the wrench, or to

fit one or both of the jaws for that purpose; 50 but that plan soon causes the wrench to be injured and unfitted for use as a wrench by the battering it receives. To remedy this, and to provide without appreciable increase of expense a hammer-face upon the wrench, I make 55 a separate hammer-head consisting of a face, *e*, and shank *f*, as shown in Fig. 4. This shank is rectangular, preferably, and may be clamped in the angular jaws. I prefer to make the shank *f* equal in length to the angular jaws, 60 so that when the end of this shank rests upon the side of the shank *a* between the jaws the head *e* shall also bear against the edges of said jaws; but this is not essential. This hammer-piece may be kept in the jaws ordinarily when 65 the wrench is not in use, or is used as a hammer, and may be removed when the instrument is to be used as a wrench. It may be made at a trifling expense, and renders the wrench equally serviceable as a hammer.

In this form of wrench I do not connect the nut to the arm of the movable jaw, it being a much cheaper construction to make the parts detached. This, however, leaves the movable jaw free without restraint, except when the 75 nut jams it against the object held between it and the fixed jaw. In order chiefly to remedy this objection, I form in the shank *a* on that side which lies under the arm *a* a shallow recess, *l*, fitted to receive and retain a bowed spring, 80 *m*, made of thin steel-plate. The sleeve and arm of the movable jaw hold this spring to the cavity, and the friction of the spring against the surface of arm and sleeve holds the movable jaw with sufficient stability.

I claim as my invention—

In combination with a wrench having the jaws made with angular recesses, the hammer-piece consisting of a face and shank, the shank being adapted to the angular recesses of the 90 jaws, all as set forth.

In testimony whereof I have signed my name to this specification in the presence of two subscribing witnesses.

HENRY ARTEMAS THOMPSON.
